Patented Mar. 21, 1922.

Inventor:
Ernest C. Lyon
By James T. Parker,
his attorney.

UNITED STATES PATENT OFFICE.

ERNEST C. LYON, OF LONG BEACH, CALIFORNIA.

BRUSH.

1,410,203.

Specification of Letters Patent. Patented Mar. 21, 1922.

Application filed March 8, 1921. Serial No. 449,383.

To all whom it may concern:

Be it known that I, ERNEST C. LYON, a citizen of the United States, residing in Long Beach, in the county of Los Angeles and State of California, have invented new and useful Improvements in Brushes; and I declare the following to be such a full, clear, and exact disclosure of the invention that anyone skilled in the art to which 10 is appertains may make and use the same.

This invention relates generally to brushes, and particularly to toilet brushes, such as hair, clothes, and the like; the specific object of the invention being to provide a brush of this character so constructed that it may be easily and conveniently folded into a compact case, suitable for carrying in the pocket or baggage, and easily and quickly adjusted for use.

20 The improved features embodied in the construction may be broadly stated as comprising a plurality of bristle supports, revolvably mounted within a case, which also serves as the back of the brush, and interconnected so the bristles can be either foldable within the case for carrying, or extensible therefrom for use.

The details of construction and operation of the invention will be more fully set forth 30 in the following specification, reference being made therein to the accompanying drawings, forming a part thereof, and in which—

Fig. 1 is a plan view of the brush showing the bristles folded within the case, and 35 with the cover removed; Fig. 2 is a longitudinal sectional elevation of the same taken on the line 2—2 of Fig. 1; Fig. 3 is an end elevation of the device as shown in Fig. 2, the view being taken as indicated 40 by the line 3—3 of Fig. 2; Fig. 4 is a view similar to Fig. 3, only taken as indicated by line 4—4 of Fig. 2; Fig. 5 is an enlarged fragmentary plan view of one of the bristle supports; Fig. 6 is a transverse vertical 45 section of the same, being taken as indicated by the line 6—6 of Fig. 5; and Fig. 7 is a fragmentary sectional view similar to Fig. 2, only showing the bristles in operative position.

50 Referring now to the drawings the numeral 10 designates generally the case in which the brush elements and their operating mechanism are enclosed, consisting of a bottom portion 11, and a cover or removable top portion 12. This case may be advantageously constructed in the con-

figuration shown in the drawing, and may be formed of metal or other suitable material. Both the bottom and top portions are similarly formed each with ends and 50 corners rounded, so as to present a neat and symmetrical outer appearance, and, also, so the bottom portion can be conveniently grasped by the hand, as a back for the brush, when the bristles are extended for 55 use. The cover portion 12 is adapted to extend over and overlap the top edges of the lower portion 11, as shown in Fig. 2, slots 13 being cut in one end of the lower portion 11, just below its top edge, and complementary tongues 14 formed integral with the lower edge of the cover 12, the tongues 14 being adapted to extend into the slots 70 13 for holding the two portions together when the cover is down. A spring catch 75 15, is mounted, by means of a rivet 16, to the inner face of the lower member 11, at its opposite end; the said catch having a detent 16a adapted to engage a notch in the cover 12 to hold the two members of the 80 case together at this end. A button 17 on the catch 15 extends through an aperture 18, in the lower portion 11, this being provided as a means for pressing the catch 15 back and disengaging the detent 16 from 85 the notch when it is desired to remove the cover 12. For convenience, a mirror 19 may be removably carried inside the cover 12, grips 20 being provided therein for retaining this mirror in place. As the cover 90 12 is adapted to be entirely removed from the lower portion 11 when the brush is in use, the mirror 19 need not be disengaged for use from the cover 12 unless desired.

The brush proper comprises a plurality of 95 cylindrical bristle supports 21, each having shafts 22 extending axially through their centers and extending from their ends, by means of which they are revolvably journaled in longitudinal supports 23 in the lower portion 11. The supports 23 may be constructed of thin sheet metal, each having their ends bent as at 24, by means of which ends they are secured to the sides 25 of the lower portion 11, so the portions 23 will extend outwardly a short distance therefrom, as clearly 100 shown in Fig. 1. The ends 24 may be secured to the side 25 in any suitable manner as by soldering or riveting. It will be noted by reference to Fig. 2 that the bearing supports 23 are so mounted in the lower portion 11 that the bristle supports will be mounted 105 110

with their peripheries extending a very short distance above the upper edge of the lower portion 11; so that when the cover 12 is removed and the bristles are extended to operative position, they will project well above the upper edge of the lower portion.

The cylindrical bristle supports 21 are preferably constructed of wood, or a like material, and are formed by cutting away a portion of the periphery to form a flat surface 26 from end to end thereof; a longitudinal channel 27 having an arcuate bottom 28 concentric with the axis of the member being then cut downwardly into the support from the surface 26. The radius of the arcuate portion 28 of the channel 27 is preferably the same as that of the shaft 22, so the latter may be inserted in the bottom thereof, and the space above it filled with a suitable cement, glue, or other retaining material 29, up to a level with the plane of the surface 26. While it is obvious that the center of the supports 21 may be bored out from end to end to accommodate and receive the shafts 22, the aforementioned means of constructing these elements is preferable for the reason that it combines a simple method of manufacture, and also enables the shafts 22 to be rigidly secured within the support 21 in a very simple and efficient manner.

The bristles 30, being of any desired length, are secured to the supports 21 by forming a plurality of transverse grooves 31 in the co-planar surfaces 26, into each of which several of the bristles 30 are laid, and secured therein by means of cement or glue, the material 29 used for securing the shafts 22 in the supports 21 preferably being used for this purpose, and the bristles being applied at the same time the shafts 22 are set. After the bristles 30 have been set in the transverse grooves 31, as shown in Fig. 5, and while the cement 29 is still soft, a strip 32 of fabric or other suitable material is then laid over the surfaces 26, to further insure a rigid mounting of the bristles 30, this strip being retained by the material 29.

It will be noted from an examination of Fig. 1 that the bristle supports 21 extend almost entirely across the lower case portion 11, being sufficiently shorter to permit being mounted in the supports 23. Each of the supports 21 are mounted in the supports 23 as near together as possible, only sufficient space being left between them to admit of their operation to move the bristles 30 from operative to inoperative position, and vice versa, as shown in Figs. 2 and 7. When the supports 21 are rotated to bring the bristles 30 within the case, or into inoperative position, the bristles of each adjacent support will overlap and rest upon the top of the bristles of the next adjacent support, as shown in Fig. 1. And in order that the brush as a whole may occupy a minimum of

space within the portion 11, the supports 21, together with their bristles 30, are mounted so an equal number will be disposed on either side of the center line C of the case, the bristles on either side of this center line being adapted to point towards each other when in inoperative position as shown in Fig. 1. To admit of this construction, the bristles 30 on the two center supports 21^a are mounted in relatively staggered relation 75 so that the bristles of one will extend between the bristles of the other when in such inoperative position.

The supports 21 are all interconnected to be actuated simultaneously, and rotated an equal amount, by means of cranks 33 secured to one end of the shafts 22, the ends 34 thereof extending through apertures 35 in typical connecting rods 36 and 37. A pair of intermeshing spur gears 38 and 39 are rigidly secured to corresponding ends of shafts 22 of the two adjacent center supports 21^a. Cranks 40 and 41, respectively, radially mounted on the gears 38 and 39, each have lower ends 42 extending through perforations 43 in the connecting rods 36 and 37.

This actuating mechanism is made manually operable by means of a thumb lug 44, formed integral with the connecting rod 37, and extending upwardly therefrom to a point above the top of the supports 21, but terminating at a point below the ends of the bristles 30 when they are extended upwardly in operative position; this thumb lug 44 being adapted to be engaged by the thumb or finger to move the connecting rod 37 longitudinally of the case portion 11. It is clear that such longitudinal movement of connecting rod 37 will, through the medium of the cranks 33, rotate the supports 21 to bring the bristles 30 into operative position, as I have shown in Fig. 7. The crank 41, connecting with the spur gear 39, and the latter co-operating with the spur gear 38 to transmit the same amount of movement to the connecting rod 36, through the medium of the crank 40, will similarly actuate the bristle supports on the opposite end. It is preferred that projections 90 be formed at the adjacent ends of the connecting rods to normally bear against the side of the casing as clearly shown in Fig. 1. An indentation 91 is formed in the side of the casing to receive the projections 90 when the device is in operative position to hold the mechanism in that position.

In operation the cover 12 is removed from the lower portion 11, by releasing the detent 16 from engagement therewith, and permitting it to pivot on the tongues 14 to swing clear of one end of the lower portion, after which it is moved longitudinally and the tongues 14 withdrawn from the slots 13. After this is done the thumb lug 44 may be engaged by the finger and moved in the di-

rection indicated by the arrow in Fig. 2; this movement rotating the supports 21, through the medium of the connecting rod 37 and the cranks 33, and also rotating the 5 spur gear 39, through the medium of the crank 41, which in turn causes rotation of the gear 38, all in the directions indicated by the arrows in Fig. 1; the latter causing rotation of the supports 21 through the medium of the cranks 33 and connecting rod 36, in the direction indicated by the arrow. These movements will move the bristles 30 10 from the position shown in Fig. 1 to the position shown in Fig. 7, or from inoperative to operative position and ready for use. It is obvious that movement of the thumb lug 44 in the direction opposite to that indicated by the arrow in Fig. 1, will move the bristles from the position shown in Fig. 7 back to 15 that shown in Fig. 1, when the cover may be again attached for carrying or packing.

While I have here shown and described a preferred embodiment of my invention, it will nevertheless be understood that I reserve 20 the right to make any changes or modifications in structure which may appear to those skilled in the art and which come within the scope of the appended claims.

Having described a preferred form of my 25 invention, I claim:

1. In a folding brush of the class described, a brush case, a plurality of substantially cylindrical bristle supports revolvably mounted in the case, means to rotate 30 said supports simultaneously, said supports having longitudinal flattened surfaces lying in parallel planes, and bristles secured to said surfaces extending in planes therewith.
2. In a folding brush of the class described, a brush case, a plurality of substantially cylindrical bristle supports revolvably mounted in the case, said supports having flattened sides extending in parallel 35 planes and bristles secured to said flattened sides extending in planes therewith, the

bristles being arranged on the supports on either side of the transverse center of the case to extend towards each other, and means to simultaneously rotate the said supports on 50 each side of said center in opposite directions.

3. In a folding brush of the class described, a brush case, a plurality of bristle supports revolvably mounted in the case, 55 bristles mounted on the said supports to extend in parallel planes, said planes being tangential to their axes of rotation, and means to rotate the said supports simultaneously.

4. In a folding brush of the class described, a brush case, a plurality of bristle supports revolvably mounted in the case, bristles mounted on the said supports to extend towards the center of the case from 60 either end thereof, and to lie in parallel planes which planes are at right angles to radial lines drawn through the supports, and means to rotate the said supports on either side of said center in opposite directions.

5. In a folding brush of the class described, a brush case, a plurality of bristle supports revolvably mounted in the case, bristles mounted on said supports in planes 75 tangential to their axes, and to extend towards the transverse center of the case from either end thereof, means to simultaneously rotate the said supports on either side of said center in opposite directions, said means 80 comprising intermeshing gears on the two supports adjacent the transverse center of the case, cranks rigidly mounted on the supports on either side of said center supports, links pivotally connecting the said cranks 85 in series on either side of the center, and radial arms on the said gears pivotally connecting with said links.

In witness that I claim the foregoing I have hereunto subscribed my name this 19th day of February, 1921.

ERNEST C. LYON.
